ABSTRACT OF THE DISCLOSURE

A bilateral switch which provides sustained operation in both open and closed states. Elimination of offset voltages is accomplished by providing a voltage divider in conjunction with a pair of voltage sources which establish a voltage gradient across the voltage divider.

This invention relates to a bilateral analog switch which provides sustained operation in both the open and closed states.

A bilateral analog switch is a device which, under a first set of conditions, provides a relatively low impedance path between two terminals for analog signals of either polarity, and, under a second set of conditions, provides a relatively high impedance path therebetween. When the switch provides a low impedance path, it is in the closed or ON state. Conversely, when the switch provides a high impedance path, it is in the open or OFF state.

Analog switches are presently being employed in pulse code modulation (PCM) encoders and decoders wherein pulse amplitude modulated (PAM) signals are converted into and transmitted as a series of pulses characterizing the polarity and magnitude of the PAM signal. One type of encoding and decoding apparatus is described in my copending application Ser. No. 382,090 filed July 13, 1964. The apparatus described therein utilizes a network of attenuators connected in tandem between a reference voltage and an output terminal. The PCM signal is provided by removing and inserting selected attenuators in the network until, upon comparison, the voltage appearing at the output closely approximates the PAM signal. The removal and insertion of the attenuators is accomplished by the use of analog switches having the capability of sustained operation in both the ON and OFF states.

The switches so employed are required, due to the bilateral nature of the PAM signals, to provide ON and OFF state impedances which are independent of the direction of current flow. Also, the switches are required to make rapid transitions between the ON and OFF states with minimized transient effect. These performance needs are due to the fact that the PAM signal approximation generated for comparison by the coding apparatus necessitates a large number of switching operations in a relatively short interval of the order of a few microseconds. Further, PCM systems are provided with nonlinear coding characteristics wherein the approximations for low amplitude PAM signals are more heavily weighted so that any error introduced by transients may significantly alter the PCM signals so generated.

The reliance of PCM coding apparatus upon a comparison of the original PAM signal and a PAM signal approximation in order to generate a PCM signal requires that the switches employed therein be adjustable to initially obtain an essentially zero off-set voltage. This minimized off-set voltage should be independent of the direction of

current flow and remain essentially constant with variations in temperature.

In practice, analog switches normally comprise a pair of transistors connected in a back-to-back configuration. The back-to-back configuration refers to a switch wherein the transistors are connected in series by the direct connection of the emitters or collectors of the individual transistors. For low voltage applications wherein the signal voltages do not exceed 5 volts, the collectors of the transistors are connected with the switching signal being applied across a transformer having its secondary winding coupled between the collectors and bases of the transistors. This type of switching is known as inverted mode operation.

15 The inverted mode operation, wherein the switching signal is applied between the collector and base, is characterized by the interchanging of the normal short-circuit current gain β and the inverse β . As a result, the individual off-set voltages in this mode are inverse functions of the transistor β 's, rather than the inverse β 's. Since the inverse β of a transistor is typically about one-tenth of the normal β , the net off-set voltage of this switch is the difference between two relatively small voltages and is usually less than 1 millivolt. However, accompanying the low off-set voltage is the limitation imposed on the hold-off voltage of the switch by the reverse base-emitter rating of the transistor. Since the signal to be switched appears across this junction when the switch is in the OFF or open state, the use of this switch is limited to low-voltage applications, for example, less than 5 volts.

20 The back-to-back configuration in which the emitters of the two transistors are connected to each other enables the switch to withstand relatively high voltages when in the OFF or open state. This is due to the fact that the signal 25 to be switched appears across the collector-base junction of the transistor. The ability of this type of switch to operate at higher voltages is gained at the expense of the net off-set voltage, which now is determined by the inverse β 's of the transistors and is in the range of several millivolts.

25 As discussed above, the back-to-back switches suffer from either a low voltage rating or a relatively high net off-set voltage. In addition, both types of switch have at least one transistor which experiences the flow of current in the inverse direction between the emitter and collector. Thus, the current gain obtainable is determined by the inverse β of the transistors and therefore limited. More significantly, the use of a transformer in the base circuit of these switches renders them incapable of sustained operation in the ON or closed state, since the switching signal applied across the transformer subsequently decays toward zero.

30 Another type of analog switch which is capable of bilateral operation employs four diodes. The diodes are connected in a bridge-type configuration to form a four-terminal network in which one diode is connected between adjacent terminals. While the polarities of the diodes are such as to provide sustained bilateral operation, none of the elements incorporated in the switch can provide gain so that the gain of the switch is always less than one. The nature of the bridge circuit requires that a circulating current greater than the magnitude of the current from the signal to be switched be provided.

35 In addition, isolation impedances are coupled between the switch and the switching signal source in order to inhibit the flow of parasitic components of the signal to be switched. These impedances result in a further reduction

of the gain of the switch. Also, the off-set voltage of the switch is determined by how closely the characteristics can be matched over a wide temperature range.

Accordingly, an object of the present invention is the provision of a bilateral analog switch capable of providing gain and sustained operation in both the ON and OFF states.

Another object is to provide a bilateral analog switch having improved gain.

Still another object is to provide a bilateral analog switch having a substantially zero off-set voltage over a wide range of operating conditions.

Yet another object is to provide a bilateral analog switch which is capable of adjustment to provide a substantially zero off-set voltage without requiring the use of matched components.

A further object is to provide a bilateral analog switch having an improved transient response.

In accordance with the present invention, a bilateral analog switch is provided which comprises a first asymmetrically conductive means having third, fourth and fifth terminals and a second asymmetrically conductive means having sixth, seventh and eighth terminals. The first means is poled to pass current flowing from the third to fifth terminals, while the second means is poled to pass current flowing from the eighth to sixth terminals.

The first and second means are coupled between first and second terminals in the following manner; the third and sixth terminals are coupled to the first terminal and the fifth and eighth terminals are coupled to the second terminal. The first and second means are rendered conductive by the application of switching signals to the fourth and seventh terminals respectively. When so rendered, the first means provides a low impedance path between the first and second terminals for current flowing from the first to second terminals. Also, the second means provides a low impedance path between the first and second terminals for current flowing from the second to first terminals. Thus, the concurrent application of switching signals to the fourth and seventh terminals provides bilateral switching.

In the absence of the switching signals, the first and second means are nonconductive, i.e. in their high impedance state, so that the switch is in its open or OFF state. When the individual means are rendered conductive, the voltage across the first means when conducting may not be equal to the voltage across the second means for an applied signal of opposite polarity. To this end, balancing means such as a voltage divider, may be coupled between the fifth and eighth electrodes. The voltage divider is provided in conventional manner with an adjustable tap which is coupled to the second terminal. By varying the position of the tap and thereby adding voltage in series with the first and second means, the static composite characteristic, i.e. the bilateral curve of current versus voltage, of the switch can be adjusted so that it passes through the origin. Thus, the voltage off-set of the switch is essentially eliminated.

Each asymmetrically conductive means contains a unidirectional conducting element, such as a diode, and a three electrode semiconductor element, such as a transistor. By selecting the corresponding elements of each means to possess complementary static characteristics, the temperature variation of the individual element characteristics do not significantly alter the low off-set voltage of the switch. However, the balancing divider enables the switch to be adjusted for essentially zero off-set at different temperatures without requiring the use of matched elements.

The first means contains a first diode, having first and second electrodes, poled to pass current flowing from the first to second electrode and a first transistor having third, fourth and fifth electrodes. The third electrode is coupled to the second electrode. The first electrode is coupled

to the first terminal and the fifth electrode is coupled to the second terminal. The absence of a switching signal at the fourth electrode results in the transistor being cut-off so that the first means is nonconductive for signals of either polarity appearing at the first terminal. It will be noted that for negative polarity signals at the first terminal, the first means is rendered nonconductive by the first diode, while for positive signals, the first means is rendered nonconductive by the first transistor. The transistor is preferably connected so that the collector corresponds to the third electrode and the hold-off capability is determined by the high voltage junction. Also, the conductivity type is selected so that the transistor is not operated in inverse manner and the normal β or short-circuit current gain determines the gain of the switch.

The second means is constructed in a similar manner with the diode therein being reversed with respect to the first diode and the transistor therein being of opposite conductivity type for the above reasons. It shall be noted that the first and second means of this switch are asymmetrically conductive and provide a switching gain.

Further, the switching signals applied to the transistors need not be applied through a transformer but can be referenced to ground so that the switch is capable of sustained operation in both the ON and OFF states. Also, during the transient periods at turn-on and turn-off, a cancellation of the transient spiking is obtained due to the balanced nature of the circuit. This transient suppression is due to the concurrent application of the switching signals to the first and second means.

Further features and advantages of the invention will become more readily apparent from the following detailed description of a specific embodiment of the invention taken in conjunction with the accompanying drawings, in which:

FIG. 1 is a schematic diagram of one embodiment of the invention;

FIG. 2 is a curve showing representative static characteristics of the embodiment of FIG. 1;

FIG. 3 is a schematic diagram of the equivalent circuit of the embodiment of FIG. 1 during the transient period; and

FIG. 4 is a graph showing the variation in leakage current with temperature for the embodiment of FIG. 1.

Referring now to FIG. 1, a bilateral analog switch is shown coupled between first and second terminals 10 and 11. The switch comprises first and second asymmetrically conductive means 14 and 15 respectively each of which are poled to permit the flow of current in a single direction.

First means 14 having third, fourth and fifth terminals 16, 17 and 18, respectively, is poled to pass current flowing from terminal 16 to terminal 18. As shown, terminal 16 is coupled to first terminal 10 while terminal 18 is coupled to second terminal 11. Second means 15 having sixth, seventh and eighth terminals 20, 21 and 22 respectively, is poled to pass current flowing from terminal 22 to terminal 20. It shall be noted that terminal 20 is coupled to first terminal 10 while terminal 22 is coupled to second terminal 11.

First asymmetrically conductive means 14 contains diode D_1 having its anode electrode coupled to terminal 16 and its cathode electrode coupled to the collector of transistor Q_1 . The emitter of transistor Q_1 is coupled to terminal 18 and the base thereof is coupled to switching signal terminal 17. As shown, transistor Q_1 is an NPN transistor so that it may be rendered conductive by the application of a positive signal to terminal 17. The diode D_1 prevents first means 14 from conducting current from terminal 18 to terminal 16. However conduction from terminal 16 to terminal 18 can only occur when a positive voltage is applied to terminal 17.

Similarly, second conductive means 15 contains diode D_2 having its cathode electrode coupled to terminal 20 and its anode electrode coupled to the collector of PNP

transistor Q_2 . The emitter of transistor Q_2 is coupled to terminal 22 and the base thereof is coupled to switching signal terminal 21. The diode D_2 prevents the conduction of current from terminal 20 to terminal 22 while conduction in the opposite direction can occur only when transistor Q_2 is rendered conductive by the application of a negative signal to terminal 21.

The terminals 18 and 22 are coupled to the opposite ends of a balancing voltage divider R_1 having an adjustable tap thereon which is shown coupled to second terminal 11. Terminals 18 and 22 are coupled to voltage sources $-V$ and $+V$ through resistors R_2 and R_2' respectively so that a voltage gradient occurs along resistor R_1 . The voltage source $-V$ is coupled also to terminal 17 through R_3 . Similarly voltage source $+V$ is coupled also to terminal 21 through resistor R_3' .

The switching signals are applied to terminals 12 and 13 which are coupled to terminals 17 and 21 through the parallel combinations of capacitor C_1 and resistor R_4 and of capacitor C_1' and resistor R_4' respectively. The signals are applied simultaneously to render the transistors Q_1 and Q_2 conductive. The magnitudes of resistors R_3 and R_4 are selected so that the application of a positive voltage at terminal 12 results in the voltage at switching signal terminal 17 changing from $-V$ to a positive voltage. As a result, transistor Q_1 is driven into conduction, preferably saturation. A similar result is obtained at switching signal terminal 18 with only the polarity being different.

Assuming a positive signal appearing at terminal 10, the application of the switching signals renders transistors Q_1 and Q_2 conductive. However, diode D_2 cannot conduct current in the corresponding direction so that second means 15 is cut-off. First means 14 can conduct in this direction so that a low impedance path is provided between terminals 10 and 11. The impedance in the ON state is determined by the forward impedances of the diode and transistor and the portion of the impedance of the balancing potentiometer between terminals 18 and 11. In practice, this impedance is less than 50 ohms. For negative signals, the second means is conductive in the same manner so that the relatively low ON impedance of the switch is essentially independent of polarity.

In the absence of the switching signals, both first and second means 14 and 15 are nonconductive and the switch is in the OFF state. The OFF impedance of second means 15 is determined by the back resistance of diode D_2 while that of the first means is determined by the impedance of the back-biased collector-base junction of transistor Q_1 . In practice, the OFF impedance exceeds 5×10^6 ohms. It shall be noted that for negative polarity signals at terminal 10, the OFF impedance of first means 14 is determined by diode D_1 and the OFF impedance of second means 15 is determined by the impedance of the back-biased collector-base junction of transistor Q_2 . By employing similar diodes and transistors, the high OFF impedance of the switch is essentially independent of the polarity of the signal at terminal 10.

The state current-voltage characteristic of the switch is shown by the dotted line 30 of FIG. 2. This characteristic is the composite of the static characteristics 31 and 32 of first means 14 and 15 respectively. If the static characteristics of each branch are symmetrical, the individual off-set voltage e_1 and e_2 are of the same magnitude and the composite characteristic passes through the origin. This corresponds to the positioning of the tap of voltage divider R_1 at the point wherein equal magnitude and opposite polarity voltages are added to each branch.

However, if the characteristics of the branches are not symmetrical, corresponding to the use of unmatched elements therein, the position of the tap of voltage divider R_1 may be varied so that the composite characteristic passes through the origin. This adjustment can be made to compensate for a change in operating temperature to insure that the off-set voltage of the switch remains es-

sentially at zero. In addition, the use of complementary transistors Q_1 and Q_2 and similar diodes D_1 and D_2 minimizes any temperature variations since the net current is a function of the characteristics of both branches. Also, for certain applications the balancing divider R_1 may be omitted if desired.

The curve of FIG. 4 shows the measured leakage current for one embodiment of the invention in the absence of switching signals, i.e. the switch is open. The signal applied at terminal 10 was 20 volts and the temperature was varied from 25° to 80° C. For the typical operating temperature of less than 50° C., the leakage current was found to be less than 10 μ amps.

Since this switch is to be operated at high rates for signals having a wide range of magnitudes, the transient response to switching is of primary interest. During the switching transient interval, the equivalent circuit of the switch may be represented by the capacitive bridge of FIG. 3 wherein C_{cb1} , C_{cb1}' , C_{cb2} and C_{cb2}' refer to the junction capacitances of transistors Q_1 and Q_2 . Due to the fact that opposite polarity switching signals appear at terminals 17 and 21, there is a cancellation of both the turn-on and turn-off edges. The degree of this cancelling effect depends on the match between the capacities of the transistors and the absence of any differences between the switching signal waveforms. In practice, the transient spikes occurring at turn-on and turn-off are found to be approximately 0.1 volt and about 0.5 microsecond in duration.

Typical component values for one embodiment tested and operated were as follows:

Diodes D_1 , D_2 —Type IN 695
 Transistor Q_1 —Type 2N 2218
 Transistor Q_2 —Type 2N 2904
 Resistor R_1 —20 ohms
 Resistors R_2 , R_2' —150 ohms
 Resistors R_3 , R_3' —12 kilohms
 Resistors R_4 , R_4' —3.9 kilohms
 Capacitors C_1 , C_1' —47 picofarads

While the above description has referred to a specific embodiment of the invention, it will be apparent that many modifications and variations may be made therein without departing from the spirit and scope of the invention.

What is claimed is:

1. A bilateral analog switch comprising:
  - (a) first and second terminals;
  - (b) a first diode having first and second electrodes, said first electrode being coupled to said first terminal, said diode being poled to pass current flowing from said first to said second electrode;
  - (c) a first transistor having third, fourth and fifth electrodes, said third electrode being coupled to the second electrode of said first diode, the application of a switching signal to said fourth electrode rendering said first transistor conductive as between its third and fifth electrodes;
  - (d) a second diode having first and second electrodes, said second electrode being coupled to said first terminal, said diode being poled to pass current flowing from said first to said second electrode;
  - (e) a second transistor having third, fourth and fifth electrodes, said third electrode being coupled to the first electrode of said second diode, the application of a switching signal to said fourth electrode rendering said second transistor conductive as between its third and fifth electrodes;
  - (f) voltage divider means having third, fourth and fifth terminals, said third and fifth terminals being coupled to the fifth electrode of said first transistor and the fifth electrode of said second transistor respectively, said fourth terminal being coupled to said second terminal; and

(g) first and second voltage sources of opposite polarity, said first voltage source being coupled between the third and fourth terminals of said voltage divider means and said second voltage source being coupled between the fourth and fifth terminals of said voltage divider, said voltage sources establishing a voltage gradient along said voltage divider means so that the net offset voltage between the first and second terminals of said switch is substantially eliminated.

2. A bilateral analog switch in accordance with claim 1 in which said first and second voltage sources are coupled to said voltage divider means through first and second resistors.

3. A bilateral analog switch in accordance with claim 2, in which said first and second transistors are NPN and PNP types respectively.
